Primary Examiner—Louis S. Zarfas*Assistant Examiner*—Inga-Maria Hyttinen*Attorney, Agent, or Firm*—Stephen D. Carver[57] CLAIM

The ornamental design for a deer decoy, as shown and described.

DESCRIPTION

FIG. 1 is a perspective view of my new deer decoy design

1 Claim, 8 Drawing Sheetsshowing all of its parts combined as a whole with the line broken away at the end to indicate indeterminate length;

FIG. 2 is a perspective view of FIG. 1 on a reduced scale with my deer decoy head and neck part shown in an alternate position while remaining combined as a whole with its other parts;

FIG. 3 is an exploded perspective view of FIG. 1 on a reduced scale showing my deer decoy with its head and neck part, chest part and comb part detached for clarity;

FIG. 4 is a top plan view taken generally from above FIG. 1 and looking downwards towards the top end thereof;

FIG. 5 is a bottom plan view of FIG. 1 taken generally from the bottom of FIG. 1 and looking upwards towards the bottom end thereof;

FIG. 6 is a front elevation view of FIG. 1;

FIG. 7 is a rear elevation view of FIG. 1;

FIG. 8 is a right side elevation view of FIG. 1; and,

FIG. 9 is a left side elevation view of FIG. 1.

The broken phantom line showing of a cylindrical object and a common screw eyelet in FIG. 1, FIG. 2 and FIG. 3 are for illustrative purposes only and form no part of the claimed design.

The line is broken away and shown at a reduced length in FIGS. 4, 5, 7, 8, and 9 for convenience of illustration.
